UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR CONSTRUCTION.

Application filed May 20, 1926. Serial No. 110,392.

My invention relates to improvements in car construction and more especially to an improved car side construction for hopper cars and the like.

5 It is an object of my invention to improve the construction of a car having hoppers below the side walls, whereby the lower margins of the sides will be inwardly offset, and suitably rigidified and braced to form supporting means for said hoppers.

10 It is also an object of my invention to provide suitable construction whereby a car having inwardly offset sides extending only between body bolsters, may be suitably connected in an effective manner with the end sills of the car, and continuity of reinforcement afforded between the end sills of the car.

15 It is also a further object of the invention to adapt an offset side construction to perform the function of a load carrying chord and to brace the same against bulging and buckling and protect the parts entering into the construction thereof against corrosion.

20 25 Other objects and advantages of the invention will be more clearly pointed out hereinafter and claimed.

Referring to the drawings, Fig. 1 is a side elevational view of a portion of a hopper car embodying my improvements, a portion of the side wall at the left of the figure being broken away to better illustrate the cross-beam construction. Fig. 2 is a broken horizontal sectional view, illustrating the side wall and adjoining construction, said section being taken on a line corresponding substantially to line 2-2 of Fig. 1. Fig. 3 is an enlarged fractional sectional plan view of a portion of the car taken adjacent the outer end of the bolster, and on a line corresponding substantially to line 3-3 of Fig. 1, said view illustrating the connection between the main side wall and adjacent brace which extends from the bolster to the end sill of the car. Fig. 4 is an enlarged fractional transverse sectional view taken through the lower portion of the car side wall and hopper on a line corresponding substantially to line 4-4 of Fig. 1. Fig. 5 is an enlarged fractional transverse sectional view, somewhat similar to Fig. 4, except that the section includes one of the side stakes, said view being taken on a line corresponding substantially to line 5-5 of Fig. 1. Fig. 6 is an enlarged transverse sectional view showing approximately

one half of the width of the car, said view being taken on a line corresponding substantially to line 6-6 of Fig. 1, and Fig. 7 is an enlarged fractional vertical sectional view through the side wall construction at the bolster, said view being taken on a line corresponding substantially to a line 7-7 of Fig. 1.

In said drawings A denotes one of the side walls of the car, B one of the end walls, C the center sills, D one of the body bolsters, E one of the cross-members of the car, F the end sill of the car, G one of the side braces extending from bolster to end sill, H one of the connecting gussets between the main side wall and adjacent side brace, and J one of the discharge hoppers disposed below the side wall and center sill of the car. Only one end portion of the car is shown, it being understood that both ends of the car are of similar construction, and the number of cross-members and hoppers intermediate the body bolsters will vary depending on the length and construction of the car.

The side walls A are spaced outwardly for the major portion of the length of the car to substantially the maximum allowable road clearances, in order to gain increased carrying capacity between the side walls of the car. The side walls A are each formed of a plate 10 having a vertically extending main portion and an inwardly and downwardly bent flange 11 at the lower margin thereof, for a purpose as will be hereinafter fully pointed out. The upper margin of the car side is provided adjacent the top with a suitable rigidifying member 12, which is secured to the top margin of the plate 10, the plate 10 at the top of the car side being bent inwardly as indicated at 13 to dispose said rigidifying member 12 within the car side clearances. Adjacent the end of the car a portion of the side wall of the car as indicated at 14 is disposed inwardly of the main plane of the said car side wall thereby presenting narrowed body portions at the ends of the car. The transition from the planes of the respective walls is effected by an angularly related wall section as indicated at 15. In the recesses thus presented by the narrowed end body portions there are disposed a series of ladder treads 16.

Secured to the inwardly and downwardly inclined flange 11 of the car side plate 10 is a rigidifying member 17 which is pref-

erably in the form of a flanged member with one of its flanges 18 overlying the said flange 11 and extending in the same general direction, and having its adjacent flange 19 outstanding from the said first named flange, the member 18 extending longitudinally of the car between the body bolsters D, and being directly secured thereto and to the respective cross members E by means 10 of rivets extending through the flange 18 and the outer ends of the respective cross members.

The cross members E of the car include transverse vertical wall members 20 which 15 extend between the respective side walls and center sills of the car as shown in Fig. 6, only one half of the car being shown in said figure, but it will be understood that the construction is similar on both sides of the 20 center sill.

Connection between the side wall 10 of the car and the plate member 20 is effected by an integral flange 22 formed on one side of the plate, and a separate angle shaped member 23 on the opposite side of said plate, the said member 23 being also bent adjacent its lower portion, and extended over the inwardly directed lower margin of the car side and secured thereto by a series of rivets. 25 Connection between the transverse plate 20 and center sill C is also effected by an integral flange 24 on one side of the plate and a separate angle connection 25 on the opposite side thereof.

30 The transverse plates 20 on the opposite sides of the center sill C are tied across the plane of the center sill by an angle shaped tie member 26, and by inclined shedding plates 27—27, said last named plates together forming a transverse load shedding ridge sloping longitudinally of the car. The lower margin of each plate 20 of the cross member E is rigidified by an angle shaped member 28, said member at its outer end being bent 35 upwardly at 29, to overlap the inwardly directed portion of the car side. The said angle shaped member 28 is disposed on the side of plate 20 opposite to the vertical angle member 23, and said members overlap and 40 are united together and to the plate 20 by means of rivets 129, thereby forming a construction of great strength.

45 The crossbeam sections 20—20 are also tied to a lower plate 30 extending across the plane of the center sill. The inwardly directed portion of the car side is also tied to the crossbeam 20 by a gusset plate 31, which is secured to the outstanding marginal flange 19 of the rigidifying member 17, and to the 50 horizontal flange of the angle member 28. The respective flanges 18 and 19 of the angular member 17 are braced at suitable intervals by bracket members 32 which are riveted to the respective flanges thereof.

55 The heavy angular shaped members 17 are

preferably adapted to extend only between the body bolsters D, being connected to the outer end thereof, as shown in Figs. 3 and 7. Each bolster D includes a vertical web plate 33 having lower marginal angle shaped reinforcements 34 and 35 along the bottom edge thereof, said angles being bent upwardly as indicated at 134 and 135, to conform to the shape of the car side, and adjacent the outer end of the car side there are vertically extending inner and outer angles as indicated at 36 and 37 respectively, said last named members being connected to the vertically extending portion of the car side wall. The angles 36 and 37 are also extended downwardly, and bent as indicated at 136 and 137 respectively to conform to the shape of the inwardly directed portion of the car side. The downwardly bent portions 136 and 137 of the members 36 and 37 60 overlap the upwardly bent portions 134 and 135 of the members 34 and 35, and the overlapping portions are rigidly united to each other and to the web plate 33 by a rivet 38. The overlapping portions of the angle members thus provide continuous lateral flanges along the edges of the web plate 33 of the bolster.

65 Connection between the angle member 17, and the bolster, is effected by riveting flange 18 to the lateral flanges of the bolster where they are overlapped, and also by riveting the outstanding flange 19, of the angle member 17, to the bolster cover plate 39, which is formed to project on opposite sides of the lateral flanges on the bolster, and extended outwardly beneath the said outstanding flange 19. A jacking plate 40 is disposed beneath the end of the bolster and outstanding flange 19 of the angle member 17.

70 The angular member 17 is further secured to the car side adjacent the bolster through the medium of gusset member H which forms a connection between the end brace G, and the vertical car wall section. The gusset member H is formed with portions extending respectively above and below the brace, the upper portion being disposed between the vertical car side wall, and the outer vertical bolster connecting angle 37, 75 while the lower extension is bent inwardly to underlie flange 18 of the vertical member 17, and is secured thereto by rivets 41, said underlying portion of the gusset member being in the same plane as the inwardly bent flange 11 of the car side wall, a section of the said gusset being cut out as indicated at 139 and 140 to clear the flange 11.

80 Each brace G is extended to the end sill of the car, and suitably connected therewith at the corner post 42 in the usual manner. The length of the end sill coincides substantially with the width of the car at its narrowed end body portions, thereby permitting the use of a straight corner post,

and each end brace G is deflected inwardly as indicated at 43, to permit of the attachment of the respective ends to portions of the car in different vertical planes.

- 5 Extending transversely of the car above the body bolster is the sloping floor 44 which slopes longitudinally of the car towards the center thereof to the lower hopper J, said floor terminating at a discharge opening 45 which is adapted to be closed by a transversely extending door 46. A longitudinally extending side floor sheet 47 is secured to the car side and sloping floor sheet 44, thereby forming with the dumping door 46 the 10 hopper section J. The side floor sheet 47, as best illustrated in Fig. 4 is bent to present a vertical section 48 for attachment to the vertical side wall sheet, and is then bent to slope downwardly and inwardly as at 49 to present a shedding plane overlying the angular member 17, and thereafter it is bent downwardly at a steep angle and extended below the side of the car to form the main side wall of the hopper section J. The said 15 floor sheet 47 extends longitudinally of the car from the cross member shedding plate 27 to the sloping floor 44, thereby presenting an efficient sealing member to close the joints between the main side wall sheet and the 20 lower angular member to prevent seepage of water and moisture between the joints, and it thus retards corrosion of the parts. 25
- The sloping section 49 of the side hopper sheet is secured directly to the flange 18 of the member 17, as indicated at 50, and also by rivets 51 extending through the section 49, the member 17, and the underlying flange 11 of the side wall. The side floor sheet 47 is flanged as indicated at 52 and 53, which 30 flanges respectively are secured to the sloping floor sheets 27 and 44.

At certain intervals in the length of the car side wall vertical braces as indicated at 35 54 and 55 are disposed on the inner side of the car wall, said members being extended downwardly over the sloping portion of the side wall and riveted thereto as at 56, said construction being best indicated in Fig. 5.

50 It will thus be seen that my invention provides a strong construction which forms an adequate support for the lower hopper sections and provides for continuity of reinforcement in the car side wall between the 55 ends of the car, whereby buffing shocks may be effectively transmitted without buckling or bulging the side walls. The disposition of the outstanding rigidifying flange in the lower chord of the car side immediately at 60 the junction of the sloping car side and the lower hopper J, and the tying of the said flange to the cross members by gusset plates ensures a very rigid construction against bulging of the car sides. The formation of 65 the car side and disposition of the lower

chord member to conform to the load containing capacity of the car provides for maximum carrying capacity and the novel arrangement of the car side and side hopper floor sheet effectively protects the said lower chord where it would normally come in contact with the lading in the car.

70 While I have herein shown and described what I now consider the preferred manner of carrying out the invention, the same 75 is merely illustrative, and I contemplate all changes and modifications that come within the scope of the claims appended hereto.

What I claim is:

1. In a dump car having a discharge 80 opening, the combination with a side wall having a vertical portion and an inwardly directed lower marginal portion; of a hopper section extending below the said marginal portion; said hopper section being defined 85 by a transversely extending wall and a longitudinally extending wall, said longitudinal wall being formed to overlie the inwardly directed portion of the car side, and extended upwardly above the same and secured to 90 the vertical wall portion of the car side.

2. In a dump car, the combination with a side wall having a substantially vertical wall portion and an inwardly directed lower marginal portion; of a hopper section extending below the said marginal portion, 95 said hopper section including a transversely extending floor and a longitudinally extending wall, said longitudinally extending hopper floor being bent to overlie the inwardly directed portion of the car side and secured thereto, and also having a section extended upwardly and secured to the vertical wall portion of the car side.

100 3. In a dump car, the combination with a side wall, said side including a vertical portion and an inwardly directed lower marginal portion; a marginal reinforcing member adapted to lie upon said inwardly directed lower marginal portion of the car 110 side; floor sheets extending transversely of the car and sloping downwardly towards each other longitudinally of the car, said floor sheets lying in planes which extended intersect the said marginal reinforcing member; a longitudinally extending hopper sheet extending between said sloping hopper sheets, said longitudinal hopper sheet being secured to the vertical portion of the car side wall and extended downwardly into 120 contact with the reinforcing member; and connections between said longitudinal hopper sheet and transverse floor sheets.

115 4. In a railway car, the combination with a side wall including a plate having a vertically disposed main portion and an inwardly and downwardly directed lower marginal flange section; of a reinforcing member disposed above said flange and lying 125 against the same; a hopper section disposed

below and adjacent said reinforcing member, said hopper section including a longitudinally extending wall in contact with the reinforcing member and formed with an inclined portion and a vertical wall member adapted to overlie said first mentioned vertical wall member; securing means adapted to unite the respective vertical wall members; and securing means extending through the lower flange section of the car side, the reinforcing member, and the inclined portion of the hopper wall.

5. In a dump car, the combination with the body bolsters and end sills; of side walls having a vertical upper portion and contracted lower marginal portions, said contracted lower portions extending between the bolsters; braces extending outwardly from the bolsters to the end sills of the car, and a gusset member securing each brace to the corresponding car side wall, each of said gusset members being formed to conform to the shape of the side wall and secured to the vertical portion thereof and also to the contracted marginal portion of the same.

6. In a railway car, the combination with the body bolsters; of vertical side walls extending between the body bolsters, said vertical side walls having inwardly directed lower marginal portions; a brace extending from each body bolster to the end of the car, said brace being disposed above the inwardly directed portion of the car side; and a connecting gusset secured to each brace and to both the vertical and inwardly directed portions of the adjacent car side wall.

7. In a railway car having a wide central body portion, and contracted end body portions, said wide central portion being formed by disposing side walls outwardly, each of said walls including a vertical wall section and an inwardly directed lower margin section; a reinforcing angular shaped member secured to said inwardly directed portion of the car side; and horizontal brace members disposed at each corner of the car, each of said braces being secured at one of its ends to the wide central body portion of the car and at its opposite end to the contracted body portion of the same, and in the plane thereof.

8. In a dump car the combination with bolsters and end sills; side walls having vertical portions spaced outwardly to define substantially the maximum width of the car and having inwardly contracted lower horizontal marginal portions and contracted end body portions, said contracted lower marginal portions extending from body bolster to body bolster; braces disposed above the level of said contracted lower marginal portions and adapted to extend from the body bolsters to the end sills of the car, each of said braces being deflected in a horizontal plane whereby the brace at the body bol-

ster will be in the plane of the widest portion of the car and at the end sill will be in the plane of the contracted end body portion; and a gusset securing said brace to the car side wall, said gusset conforming to the shape of the car side wall and secured thereto at the vertical portion of the car side wall and at the contracted lower marginal portion thereof.

9. In a railway car, the combination with the car body having side walls each presenting a main vertical section and an inwardly sloping lower marginal section; of cross members extending upwardly in the plane of said vertical section of the car side wall and shaped to conform to the inwardly sloping side wall; hopper sections extending below the said car side wall, each of said sections being disposed intermediate the cross members; fixed floors sloping downwardly longitudinally of the car from the respective cross members on the opposite sides of the hopper to the discharge opening, one of said fixed floors extending below the car side to form one wall of the lower dumping hopper; a longitudinally extending hopper wall sheet extending between the respective longitudinally sloping floors, said sheet being adapted to meet the sloping longitudinal floor sheet extending below the car side and together with the same define two of the fixed walls of the hopper, said sheet being extended upwardly and bent to conform to the shape of the inwardly sloping lower margin of the car side and thereafter bent upwardly to present a vertical section for attachment to the vertical portion of the car side wall.

10. In a railway car, the combination with the car body having a side wall presenting a main vertical section and an inwardly sloping lower marginal section; of a hopper section disposed below the said side wall, said hopper section being defined by: a dumping door, a fixed floor sloping longitudinally of the car, a longitudinally extending fixed side wall, said longitudinally extending fixed side floor being extended upwardly to conform to the shape of the inwardly sloping lower margin of the car side and thereafter bent upwardly to present a vertical section for attachment to the vertical portion of the car side wall.

11. In a railway car, the combination with side walls each formed with a vertical portion and an inwardly sloping lower marginal portion; of cross members extending transversely of the car, said cross members being secured to said inwardly sloping lower margin of the car side; of a hopper section disposed below the level of said side, said hopper including a longitudinal wall extending downwardly from said inwardly sloping lower marginal portion of the car side; a reinforcing flange on the exterior of

- said inwardly sloping car side, said flange extending continuously between said cross members and across the plane of said hopper sections; and a connection between said 5 flange and respective cross members.
12. In a car of the character described having the side walls spaced outwardly to substantially the maximum width of the car, each said side wall having the lower 10 margin thereof deflected inwardly to form a sloping load shedding member; a hopper section extending downwardly from said inwardly directed portion of the car side; a flanged reinforcing member disposed beneath 15 said sloping margin of the car side, said flanged member being disposed with one flange underlying the sloping hopper section and having the adjacent flange outstanding therefrom, said outstanding flange being disposed adjacent the junction of the inwardly directed portion of the car side and the downwardly extending hopper section.
13. In a car of the character described having the side wall spaced outwardly to substantially the maximum width of the car, each of said side walls having the lower margin thereof sloping inwardly and downwardly; a hopper section extending downwardly from said sloping lower margin of the car side; a flanged reinforcing member secured by one of its flanges to the inwardly sloping portion of the car side, said member having its opposite flange outstanding 30 from the sloping side and disposed adjacent the meeting edges of said hopper section and sloping floor; and a reinforcing stake member on the inner side of the car wall formed to conform to the shape of the side wall and secured to said flanged reinforcing member and to the vertical side wall of the car.
14. In a car of the character described having the side walls spaced outwardly to substantially the maximum width of the car,
- each of said walls having the lower margin thereof deflected inwardly and downwardly; a reinforcing angular member having one flange outstanding from the inwardly deflected side, said outstanding flange being disposed adjacent the lower margin of the said car side wall; a transversely extending cross member extending to said angular member; and a gusset member connecting said outstanding flange of the angular member and the cross member.
15. In a car of the character described having a side wall formed with a vertical portion and having an inwardly directed lower marginal portion; a reinforcing angular member included in said inwardly directed lower marginal portion, said member having one flange extending in the plane of the inwardly directed portion of the car side and having the adjacent flange outstanding therefrom at the lower margin of said side; and a bracket member extending between and secured to the respective flanges of the angular member.
16. In a dump car having a discharge hopper, the combination with bolsters; of side walls, each side wall including vertical sheet metal sections with integral, inwardly diverted lower marginal portions, and a reinforcing member extending from bolster to bolster, said member being of angular cross-section and having one flange thereof overlapped on the upper side of said inwardly diverted portions; and hopper sheets secured to the side walls, each said hopper sheet having the upper portion thereof overlying the upper side of the corresponding reinforcing element and with a vertical upper marginal portion secured to the vertical portion of the side wall.

In witness that I claim the foregoing I have hereunto subscribed my name this 14th day of May 1926.

ARGYLE CAMPBELL.
